HAND TOOL CONSTRUCTION

Louis A. Pazandak, Minneapolis, Minn.

Application July 27, 1950, Serial No. 176,127

1 Claim. (Cl. 306—21)

1

This invention has relation to a hand tool consisting of an elongated handle and a working element, useful for many different purposes but herein illustrated and described as especially useful for garden work.

The object of the invention is to provide a new and improved hand tool construction through the instrumentality of which an elongated tool handle can be detachably assembled with a tool working element to the end that hand tool working elements of various types can be interchangeably employed with a single tool handle. Stated differently, the invention herein presents a novel and improved construction and arrangement for accomplishing detachable assembly of a hand tool working element and a manipulating handle therefor.

In the accompanying drawing forming a part of this specification,

Fig. 1 is a side elevational view of a hand tool construction made according to the invention;

Fig. 2 is an end elevational view of the disclosure of Fig. 1 as it would appear from the left;

Fig. 3 is a fragmentary top plan view of the hand tool construction;

Fig. 4 is a detail sectional view, taken on line 4—4 in Fig. 3;

Fig. 5 is a detail sectional view, taken on line 5—5 in Fig. 1; and

Figs. 6, 7 and 8 are sectional views corresponding generally with the disclosure of Fig. 5 but showing hand tool constructions each of modified type made according to the invention.

With respect to the drawing and the numerals of reference thereon, 10 denotes an elongated handle and 11 indicates a working element of a hand tool. As shown, the working element 11 is suitable for a type of garden work. It is to be understood, however, that the working element of a tool detachably assembled with an elongated handle such as 10 according to the principle of the invention could be of structure suitable for accomplishing almost any type of work. By way of example, a working element when detachably assembled with a handle such as 10 could provide, together with said handle, a rake, hoe, shovel, spade, axe, etc., each of type as may be selected to the accomplishment of a particular job.

The working element 11 includes a carrying frame 12 integrally supported by a flat blank or strip 13 of rigid material, metal as shown, constituted as a part of an L-shape handle retainer, represented generally at 14, of the tool construction. The handle retainer 14 and the flat blank or strip 13 thereof are situated between the car-

2

rying frame 12 and the elongated handle 10. In the disclosure as made, the carrying frame 12 integrally or rigidly supports a blade 15 useful for hoeing, but said carrying frame could support a working instrument of any type which might be selected, and to this end the carrying frame could be of any preferred configuration.

The L-shape handle retainer 14 is composed as a longer arm adjacent the elongated handle 10 and a shorter arm adjacent the carrying frame 12 and integrally connected with the longer arm in the plane thereof. Said longer arm of the handle retainer is constituted as a first hollow element bounded at the top thereof, or portion opposite the flat blank or strip 13, by a straight first elongated wall 16 and at opposite sides thereof by spaced, parallel walls 17, 17. Said longer arm or first hollow element is open at the bottom thereof, or portion adjacent said flat blank or strip. Said shorter arm of said handle retainer is constituted as the flat blank or strip 13 and a second hollow element bounded at the front thereof, or portion opposite said flat blank or strip, by a curvilinear second elongated wall 18 and at opposite sides thereof by spaced, parallel walls 19, 19. Said second hollow element is closed at the rear thereof, or portion adjacent the longer arm or first hollow element, by the flat blank or strip 13, and the second hollow element is substantially closed at the end portion thereof spaced from said longer arm or first hollow element. As shown, the walls 19, 19 integrally support flange portions 20, 20 which extend exteriorly therefrom in perpendicular relation thereto to which the flat blank or strip 13 is rigidly secured, as at 21, in closing relation to the rear, or portion adjacent the longer arm or first hollow element, of the second hollow element of the handle retainer 14. Together, the first and second hollow elements provide a continuous passage, composed as a guideway 22 and a pocket 23 open to the front of the guideway, bounded or defined at its upper and forward portions by the first and second elongated walls 16 and 18 and at its opposite sides by the walls 17, 17 and 19, 19, and closed at the rear of the pocket 23, or portion adjacent the longer arm or first hollow element, by the flat blank or strip 13. Forward and lower parts of the pocket 23 are bounded by a curvilinear surface 24, provided by the second wall 18, which faces rearwardly in adjacent relation to an upper portion of a forward surface 25 of the flat blank or strip 13 and the guideway 22 provided by the longer arm or first hollow element of the handle retainer 14. An upper part of the guideway 22,

or portion opposite the open side of the longer arm or first hollow element of said handle retainer, is bounded by a straight surface 26, provided by the first wall 16, which faces downwardly. The bounding surfaces 25 and 26 are in spaced, substantially perpendicular relation, at opposite sides of said guideway 22, and the curvilinear bounding surface 24 is disposed between and forwardly of said bounding surfaces 25 and 26, as well as in substantially perpendicular relation to the bounding surface 26.

The elongated handle 10 is rigid with a straight shank 27 of reduced diameter terminating at the attaching end of said handle in a hook portion 28 which faces or opens rearwardly in the plane of said shank 27 in substantially perpendicular relation thereto. As shown, the hook portion 28 extends through an arc of substantially 180 degrees, and the shank 27 and said hook portion are of equal thickness.

The L-shape handle retainer 14 is adapted to removably receive the shank 27 and hook portion 28 of or on the handle 10, and to this end an interior marginal edge 29 of the flat blank or strip 13 is spaced from the elongated wall 16 bounding the upper portion of the guideway 22 a distance greater than a measurement representing the thickness of said shank and less than a measurement representing the overall length of said hook portion. The side walls 17, 17 and 19, 19, respectively, are spaced apart a distance substantially equal to the thickness of the shank 27 and the hook portion 28, and the curvilinear surface 24 is of arc and situated relative to the downwardly facing surface 26 provided by the wall 18 and the forward surface 25 of the blank or strip 13 to snugly seat the forward surface of the hook portion 28 when the shank 27 is engaged against said downwardly facing surface 26 and a rearwardly facing free end 30 of said hook portion 28 is engaged against said forward surface 25, as in Fig. 4 of the drawing.

The shank 27 slidably supports a tubular element or locking ring 31 for movement longitudinally of said shank adapted to be removably assembled with the rear ends of the walls 17, 16, 17 of the longer arm or first hollow element of the L-shape handle retainer 14 thus to be capable of rigidly securing said shank in said retainer when assembled therewith. As disclosed, a compression coil spring 32 upon the shank 27, having one of its ends engaged against the handle and its other end engaged against the tubular element or locking ring 31, normally urges the latter longitudinally of said shank, and the adjacent, rearward ends of the walls 17, 16, 17 are of configuration to be snugly fitted into an annular concavity 33 in the forward end of said tubular element or locking ring.

The manner in which the elongated handle 10 and the working element 11 are assembled and disassembled will be apparent. To accomplish assembly of said handle and working element, the hook portion 28 and the shank 27 are inserted in the guideway 22 and slid to position, while the tubular element or locking ring 31 is retained in a retracted position against force of the compression coil spring 32, to cause said hook portion to be seated in the pocket 23 against its curvilinear surface 24, said shank to be engaged against the downwardly facing surface 26 and the rear end 30 of the hook portion to be engaged against the forward surface 25 of the flat blank or strip 13, and upon completion of assembly of the handle and working element said

tubular element or locking ring is released thus to permit said compression coil spring to cause said tubular element or locking ring to be fitted upon the adjacent end of the longer arm or first hollow element of the handle retainer, as in Fig. 4. It will be obvious that assembly of the shank and hook portion of or on the handle with the retainer can be accomplished by relative rocking movement of said handle and retainer. The rear end of the hook portion can be made to enter the pocket while the shank is spaced from the downwardly facing surface 26, and after said rear end of said hook portion is in said pocket, at position forwardly of the blank or strip 13, the handle with shank can be swung toward the wall 16 to complete the assembly. Disassembly can be accomplished by first removing the tubular element or locking ring 31 from the rear end of the longer arm or first hollow element of the handle retainer and then swinging the shank 27 away from the wall 16 until the hook portion 28 is withdrawn from the pocket 23.

Obviously, the handle and working tool when assembled, as in Fig. 4, will be rigidly secured together against the possibility of relative movement. Relative rotative movement of the shank with hook portion and the longer arm or first hollow element is precluded by reason of said hook portion being seated in the pocket 23, relative rocking movement of the handle and retainer is precluded by reason of the tubular element or locking ring 31 being fitted upon the rear end of said longer arm or first hollow element, relative longitudinal movement of said handle and retainer is precluded by cooperative action of the hook portion rear end 30 engaged against the forward surface 25 of the blank or strip 13 and said tubular element or locking ring, and relative transverse movement of said shank and hook portion and handle retainer is precluded by the side walls 17, 17 and 19, 19 and the fit of the hook portion to the curvilinear surface 24. Stated broadly, parts of the handle and working element cooperate when these are assembled to cause them to be rigidly secured to each other. At the same time, said handle and working element are capable of being readily and easily assembled and disassembled.

In Figs. 1 to 5 of the drawings, the shank 27 is circular in cross section, and the downwardly facing surface 26 is of part-cylindrical configuration in order that said shank can be snugly fitted to it.

In Fig. 6, the shank 27^a is hexagonal in cross section and the downwardly facing surface to be engaged by said shank is of configuration to correspond. In Fig. 7, the shank 27^b is square in cross section and the downwardly facing surface to be engaged by it is of configuration to correspond. In Fig. 8, the shank 27^c is triangular in cross section and the downwardly facing surface it is to engage is of similar configuration. Otherwise than as stated, the construction as in Figs. 6, 7 and 8 is, or may be, the same as in Figs. 1 to 5. The disclosures of said Figs. 6, 7 and 8 illustrate that the shank need not necessarily be cylindrical. Shanks of configuration other than as shown evidently can be employed.

What is claimed is:

The combination with a working element and a handle including an elongated shank and a hook portion upon an end and in the plane of said elongated shank, of mechanism detachably securing said working element upon said elongated shank and hook portion comprising an L-shape retainer composed as a first arm adja-

cent said elongated shank and constituted as a first hollow element formed to snugly, removably receive said elongated shank and a second arm adjacent said hook portion and rigid with both said first arm and said working element and constituted as a second hollow element formed to snugly, removably receive said hook portion, said first hollow element being bounded at the side of said second hollow element opposite said working element by a first surface situated in facing relation to the second arm and at opposite sides of said first surface by spaced surfaces extending toward said second arm, said second hollow element being bounded at the front thereof by a second surface situated in facing relation to said first arm and at opposite sides of said second surface by spaced surfaces extending toward said first arm and at the rear thereof by a surface rigid with said working element, the first and second hollow elements being in open, contiguous relation to each other, said hook portion lying in said second hollow element in engaged relation with said second surface

10

20

when said surface rigid with said working element when said elongated shank is situated in said first hollow element in engaged relation with said first surface, and means detachably fastening a part of said first arm spaced from said second arm upon a part of said elongated shank.
